UNITED STATES PATENT OFFICE.

LOUIS MARIE GABRIEL DELAUNAY-BELLEVILLE, OF PARIS, FRANCE.

FEED-WATER HEATER.

SPECIFICATION forming part of Letters Patent No. 590,830, dated September 28, 1897.

Application filed February 20, 1897. Serial No. 624,365. (No model.)

To all whom it may concern:

Be it known that I, LOUIS MARIE GABRIEL DELAUNAY-BELLEVILLE, a citizen of France, residing at Paris, France, have invented certain new and useful Improvements in or Connected with Steam-Generators and Feed-Water Heaters Therefor, of which the following is a specification.

My invention consists in the combination, with steam-generators, of a novel feed-water heater or "economizer" which is in two parts or sets, one of which is placed above the steam-generating chambers or tubes, while the other is arranged at the side in the rear or above the boilers in a descending or ascending smoke flue, conduit, or channel, there being interposed between the two parts or sets of the economizer a second or supplementary gas-combustion chamber.

In order that my invention may be clearly understood, I represent in the accompanying drawings constructions according to my invention from which its nature and the manner in which it can be performed to meet varying requirements will be readily understood.

Figures 1 to 4 represent a group of boilers provided with an economizer constructed in accordance with my invention, Fig. 1 being an elevation of the group, the left half of the figure being in elevation and the right-hand part in longitudinal section, the section being taken on the line A B, Fig. 3. Fig. 2 is a plan partly in horizontal section on the line C D, Fig. 1, and partly in horizontal section on the line E F, Fig. 1, the steam-producing tubes not being shown in this figure. Figs. 3 and 4 are transverse sections upon the lines G H and I J, Fig. 1, respectively. Figs. 5 to 8 illustrate a modified construction, Figs. 5 and 6 being, respectively, a longitudinal section on the line K L, Fig. 7, and a longitudinal elevation, and Figs. 7 and 8 being transverse sections on the lines M N and O P, Fig. 5, respectively. Figs. 9 to 11 represent a further modification, Fig. 9 being partly a longitudinal elevation and partly a longitudinal section on the line Q R, Fig. 11. Fig. 10 is a horizontal section on the line S T, Fig. 9; and Fig. 11 is a transverse section on the line U V, Fig. 9.

In all the figures the barbed arrows indi-

cate the course of the combustion-gases and the barbless or plain arrows indicate the direction in which the feed-water circulates. 55

1 1 2 2 are the steam-generating chambers of the boilers.

3 3 4 4 are the chambers of the economizers placed above the boilers, there being one economizer for each boiler. 60

5 5 6 6 designate the additional combustion-chambers interposed between the steam-producing chambers 1 2 and the economizer-chambers 3 4.

7 8 are the economizer-chambers placed beside and between or above the boilers. They are within compartments situated beside, below, or above the smoke-flue leading to the chimney. The chamber 7 serves as one common economizer for all the boilers at the same side with itself, while the chamber 8 is an economizer common to the boilers on the other side. 65

9 10 are smoke-flues forming an additional combustion-chamber between the economizer 7 3 and 7 and 4 and 8, respectively. 75

11 and 12 are smoke-flues next in order to the economizers 7 and 8, the cleaning of which smoke-flues is effected by means of the doors 13 and 14. 80

15 15 are smoke-flues leading to the chimney, and 16 17 are the boiler-furnaces, having charging-doors 18 18 and ash-pit doors 19 19.

The feed-water enters each boiler-front 85 through a pipe 20, which conducts it into the lower collector 21 of one of the common economizers, say 7. The water runs through the chambers of such economizer and passes on to its upper collector 22, whence it issues 90 through the pipe 23, which passes to the right and left. From the pipe 23 the pipes 24 24 branch off and these conduct the water to the feed-water regulators 25 25 of the boilers. In the case of each boiler the pipe 26 conveys 95 the feed-water from the self-controlling feed-regulator 25 to the corresponding economizer 3, the water traversing the pipes of such economizer vertically either in the upward or in the downward direction or horizontally, 100 or both vertically and horizontally, in alternate succession, and issues through the pipe 27, which conducts it to the feeding-injector 28, placed upon the purifying-collector 29,

through which injector the water enters the boiler proper.

If the vertical space available be insufficient to admit more than one of the economizers 3 and 4, to be situated on either side, one only is used—namely, the one that is nearest to the smoke-flue—the gases from the terminal boilers being brought down below the economizer which is retained, say 3.

10 This economizer 3, moreover, will in that case receive through the pipe 23 direct the water which is leaving the economizer 7, and the pipes 24 24 will then conduct the water from the economizer 3 to the feed-water regulators of the boilers placed on the same side as this economizer, the pipes 26 26 will be dispensed with, while the pipes 27 27 will lead from the feed-regulators to the injectors direct.

15 My invention affords the following advantages:

First. In the event of scarcity of available space in the direction of height, provided there is sufficient space in the horizontal plane, the number of tubes in the economizer 25 of each boiler may be reduced, while the economizers may be made to retain a sufficient heating - surface by connecting them with the economizer placed beside or in the rear of the boilers or within the vertical 30 smoke-flue forming the base of the chimney.

Second. Where ample space is available both vertically and horizontally, so that the necessity of reducing the number of tubes of the economizer of each boiler is avoided, the 35 heating-surface will in consequence be materially enlarged.

Third. Where combustion is conducted on a large scale—say at the rate of from one hundred and fifty to two hundred kilograms 40 per hour and per square meter of grate—and where the fuel used is soft coal and the gases may not be entirely consumed when they have passed into the economizers placed above the boilers and where want of space 45 in height has narrowed down the reheating-surface of these last-mentioned economizers the second or additional combustion-chamber will prove very serviceable in completing the combustion.

50 Fourth. Owing to the furnaces being charged periodically fluctuations occur in the

activity of the combustion, and more particularly in the volume of the gases arising from the furnace, whence there result changes in the temperature of those gases which have 55 passed beyond the economizers situated above the boilers. The economizer situated within the smoke-flue being common to several boilers enables any surplus heat which the gases may still retain on leaving the first feed-water 60 economizers to be utilized.

Fifth. The feed-water undergoes its preliminary heating by contact with those gases which are least heated, and in its progress through the first economizer, as well as during its passage hence into the succeeding economizer, it gradually meets with more and more highly heated gases, which arrangement is calculated greatly to assist the process of absorption of the heat of the gases by 70 the water.

Sixth. Altogether by reason of the wide heating - surface wherewith the economizer situated within the smoke-flue at the foot of the chimney may be provided, whether or not 75 it be common to a number of boilers, that economizer first receives feed-water at the lowest temperature and absorbs the heat from the gases in a more complete manner than the economizer placed above the boiler could 80 do alone.

Having now particularly described and ascertained the nature of this invention and in what manner the same is to be performed, I declare that what I claim is—

85 The combination with a plurality of boilers and boiler-furnaces, and a smoke-flue common to all of them, of two sets of feed-water heaters or economizers, one set being arranged over the boilers and the other set in 90 the smoke-flue, and an auxiliary or supplemental gas-combustion chamber interposed between the two sets of feed-water heaters or economizers, substantially as described.

In testimony whereof I have hereunto set 95 my hand in presence of two subscribing witnesses.

LOUIS MARIE GABRIEL DELAUNAY-BELLEVILLE.
